CONFECTIONER'S SPLITTING TOOL

Clayton H. Ericson, 2325 Winnetka Ave. N.,
Minneapolis, Minn. 55427

Filed Feb. 3, 1969, Ser. No. 15,596

Term of patent 14 years

Int. Cl. D8—02

U.S. Cl. D8—98

FIG. 1

FIG. 4

FIG. 2

FIG. 5

FIG. 3

FIG. 6

FIG. 1 is a top plan view of a confectioner's splitting tool embodying my new design;

FIG. 2 is a bottom plan view of the same;

FIG. 3 is a left side elevational view of the same;

FIG. 4 is a rear end elevation view of the same;

FIG. 5 is a front end elevational view of the same; and

FIG. 6 is a right side elevational view of the same.

I claim:

The ornamental design for a confectioner's splitting tool, as shown and described.
